UNITED STATES PATENT OFFICE.

LOUIS G. PACENT, OF WINFIELD, NEW YORK, ASSIGNOR TO PACENT ELECTRIC COMPANY, INC., OF NEW YORK, N. Y., A CORPORATION OF NEW YORK.

VARIABLE-RESISTANCE DEVICE.

Application filed September 12, 1923. Serial No. 662,197.

To all whom it may concern:

Be it known that I, LOUIS G. PACENT, a citizen of the United States, residing at Winfield, in the county of Queens, State of New York, have invented certain new and useful Improvements in Variable-Resistance Devices; and I do hereby declare the following to be a full, clear, and exact description of the invention, such as will enable others skilled in the art to which it appertains, to make and use the same.

This invention relates to variable electrical devices, and, more particularly, variable resistance devices including rheostats and 15 potentiometers.

One object of the invention is to provide an improved device of the character referred to which can be operatively mounted on a panel (as in a radio receiving set) or 20 on a board or table for experimental or temporary circuit set-ups optionally and which does not have to be disassembled to such an extent as to put it out of adjustment in mounting or in changing from one type of 25 mounting to another.

Another object is to provide a rheostat or potentiometer of sturdy and reliable construction in which the assembled elements form a self-contained unit which is adapted 30 to be permanently adjusted at the factory, requiring no further adjustment on the part of the user.

Consonant with the foregoing objects, a rheostat or potentiometer typifying the preferred embodiment of the invention comprises a base of insulating material on which is mounted an arcuate resistance element, an apertured metal bushing journaled in the base, and a contact arm secured to the bushing and adapted to be rotated therewith for wiping over the resistance element. The base is provided with screw holes for mounting it on the back of a panel or the top of a table. A shaft for rotating the bushing, together with a contact arm of proper size to fit the aperture in the bushing, may be inserted from either end of the bushing. Thus, if the rheostat or potentiometer, as the case may be, is mounted on the back of a panel, the shaft may be inserted through an aperture provided in the panel into the bushing and there secured by a set screw or other suitable means. On the other hand, if the device is mounted on a table top or board, 55 the shaft is inserted into the bushing from

the opposite end as compared with the case above referred to, in which it is mounted on the back of a panel. Shifting the operating shaft from one position to another as above described is effected without disturbing the 60 adjustment of the device—this being one of the important features of the invention.

Other novel features of the invention will be pointed out in the following detailed description and appended claims.

Referring to the accompanying drawing,

Fig. 1 shows a fragmentary portion of a panel with a potentiometer mounted thereon;

Fig. 2 is a cross-sectional view of the panel and potentiometer taken along the line 2—2 70 of Fig. 1;

Fig. 3 is an elevational view of the potentiometer with the panel shown in cross section;

Fig. 4 is a plan view of the potentiometer 75 showing the contact arm;

Fig. 5 is a plan view corresponding with Fig. 4 but showing the operating shaft and knob adapted for mounting on a table top or 80 board;

Fig. 6 is an elevational view showing the potentiometer mounted on a table top with the operating shaft inserted in the side opposite that in which it is shown inserted in Fig. 3; and

Fig. 7 is a perspective view of the resistance element forming a part of the potentiometer.

A cylindrical base 1 of molded insulating material is formed with a peripheral shoulder 1^a against which an arcuate resistance element 2 is positioned. Resistance element 2 comprises a strip of flexible insulating material 2^a such as fibre or the like around which is wound a large number of turns of 95 resistance wire 2^b. Three binding posts 3, 4 and 5 each comprising a round head machine screw 6, washer 7, lock nut 8 and slotted nut 9 are mounted on the base 1 and rigidly secured thereto. The two ends of 100 the strip of insulating material 2^a are each provided with an aperture for engaging screws 6 of binding posts 3 and 5 and the two ends of the resistance wire 2^b are connected respectively to the binding posts 3 105 and 5.

The base 1 is provided with a central aperture 1^b in which is journaled a metal bushing 10 having a hexagonal head 10^a which is tapped to receive a small set screw 11. On 110

the reduced end portion of the bushing 9 there is assembled a dished spring washer 13 and a plain washer 12. The reduced end of bushing 10 is riveted over against the washer 12 as shown in Fig. 2, whereby these parts are permanently secured together. The spring washer 13 is provided with an integral tail piece 13^a which connects with binding post 4, as shown most clearly in Fig. 2. A contact arm 14 adapted to effect wiping engagement with the resistance wire 2^b, is formed, as shown in Fig. 4, to engage the hexagonal head 10^a of the bushing 10. Contact arm 14 is thus seen to be rotatable with the bushing 10 and is electrically connected through the medium of bushing 10, spring washer 13 and tail piece 13^a with binding post 4. A shaft 15 having a flat side 15^a milled thereon is adapted to fit the aperture in bushing 10, the flat side of the shaft being engageable by the end of set screw 11, whereby the shaft is adapted for rotating the bushing 9 together with contact arm 14. Shaft 15 is preferably provided with a molded knob of insulating material 19.

When the potentiometer is mounted on a panel as shown in Figs. 1, 2, 3 and 4, the shaft 15 is inserted through the panel and into the aperture in bushing 9, as is clearly shown in Fig. 2, and is secured in place by the set screw 11. When thus mounted the base 1 is secured to the panel by means of screws 16 which engage nuts 17.

When it is desired to mount the potentiometer on a table or board for experimental purposes, the nuts 17 can be removed and the device mounted as shown in Fig. 6 by means of a pair of wood screws. In the latter instance the shaft is inserted from the opposite end by the bushing 9 as compared with Fig. 2. It will be noted that shifting the shaft from one side to the other for the purpose of mounting on a panel or table top respectively involves only loosening the set screw 11, removing and reinserting the shaft in the position desired, and again tightening the set screw. This does not involve any dislocation of the contact arm or in any way interfere with its proper adjustment. This makes it possible to properly adjust the contact pressure of the arm 14 against the resistance wire with the assurance that it will remain so adjusted throughout the normal life of the device. 55

A punched metal part 18, shown most clearly in Figs. 4 and 5, is preferably, but not necessarily, provided with which the contact arm 14 may be engaged when it is desired to entirely cut out the resistance between terminals 4 and 5. If desired, an additional member similar to 18 may be mounted on binding post 3.

It is quite obvious that the device illustrated and described can be utilized as a 65 rheostat, in which event one of the binding posts 3—5 would not be employed as a terminal.

I claim:

1. In a variable resistance device, a base 70 adapted for mounting on a panel, a pair of spaced terminals mounted on said base, a resistance element comprising an arcuate strip of insulating material having a resistance wire wound thereon, said element being mounted on said base and secured at its ends by said terminals; at least one of said terminals being electrically connected to said wire, a rotatable contact arm for wiping over said resistance wire, a punched metal 75 terminus secured to one of said terminals and adapted to engage said contact arm for cutting said resistance wire out of circuit, and means for rotating said contact arm.
2. In a variable resistance device, a base, 80 an arcuate resistance element secured to said base, a bushing extending through said base, said bushing having a polygonal head, a contact arm engaging said resistance element and adapted to wipe thereover, said 85 contact arm having an aperture through which said bushing extends and formed to engage a plurality of sides of said polygonal head to effect a driving engagement therewith, and means operable to rotate said 90 bushing and, in turn, said contact arm.

In testimony whereof I affix my signature.

LOUIS G. PACENT.
